UNITED STATES PATENT OFFICE.

WILLIAM F. BOSSERT, OF UTICA, NEW YORK.

FISH-PLATE FOR RAILWAY-RAILS.

SPECIFICATION forming part of Letters Patent No. 789,482, dated May 9, 1905.

Application filed January 7, 1904. Serial No. 188,013.

To all whom it may concern:

Be it known that I, WILLIAM F. BOSSERT, a citizen of the United States, residing at Utica, in the county of Oneida and State of New York, have invented certain new and useful Improvements in Fish-Plates for Railway-Rails, of which the following is a specification, reference being had therein to the accompanying drawings.

10 My invention relates to a fish-plate for railway-rails; and it consists in the mechanism hereinafter more completely described and claimed in this specification.

15 The object and purpose of my invention is to furnish a cheap and reliable fish-plate for connecting the ends of the rails used in the construction and operation of railroads, which consists in the mechanism hereinafter more fully described and claimed.

20 In the drawings, Figure 1 is a perspective view of the joints of railroad-iron and the fish-plate joints connected therewith located on a railroad-tie, broken lines indicating parts removed. Fig. 2 is an end view of a somewhat modified construction. Fig. 3 is an end view of a modified construction of the fish-plate.

Having described my invention with reference to the figures illustrated in the drawings, I will now proceed to describe the same with 30 reference to the mechanical construction and operation of the same, in which description similar numerals refer to corresponding parts in the several drawings.

1 represents the ordinary railroad-tie. 2 35 represents the ordinary railway-rail, having the ordinary tread 3 with web 4 and flange 5, having suitable perforations through the rail for receiving the bolts which pass through the fish-plate and the web of the rail. The fish- 40 plates are constructed to rest under and engage shoulder 6 on the under side of the tread of the rails and to engage shoulders 7 on the flange of the rail where the web commences to expand into the base forming the foot of 45 the rail, which rests upon the tie-beams and to which the same are connected by spikes or other suitable means.

The core of my invention consists in forming the fish-plates, constructed to bear against 50 the under side of the tread or head of the rail

and the upper face of the flange on each side of the rail, with a hollow 8 running lengthwise through the fish-plate. The hollow 8 may be filled, if desired, with wood strips 9, Fig. 1, or any other yielding substance running lengthwise in the center of the fish-plate. The walls of the fish-plate may be formed from a single piece of metal running vertically, as indicated at 10, having its upper and lower portions curved outwardly for engaging 60 the under side of the tread or head of the rail and the upper face of the flange and the outer wall 11 returning substantially parallel to the inner wall 10. The lower end of the returned wall may rest on the upper face of the inner 65 wall, as indicated at 12, Fig. 2, or it may rest on the flange 5 against the face of the inner wall, as indicated at 13, Fig. 1, leaving the two walls, the inner and outer wall of each fish-plate, with a space between them, which 70 secures an elastic pressure on the nuts and bolts 14, which are inserted through suitable bolt-holes in the fish-plates and in the rails, so that when the nuts are turned up on the screw-threaded bolts both are held by spring- 75 pressure in the outer wall of each fish-plate, thereby preventing in whole or in part the working loose of the nuts on the screw-threaded bolts which hold the fish-plates to their work on the railroad-joints. If desired to 80 add to the strength of the spring resistance in the fish-plates in any form of my construction, a strip of wood 9 (illustrated in Fig. 1) may be inserted in the longitudinal opening between the walls of the several fish-plates, or 85 the filling may be omitted. If desired, the fish-plates may be formed with an outer and an inner wall, the two edges of the fish-plates being so formed as to engage the under side of the head of the rail and the upper side of 90 the flange and being made by compressing a tubular piece of metal into the desired shape and with or without any seam in the periphery. In Fig. 3 I show such a kind of fish-plate, which also has a different form and 95 either edge of which may be uppermost. A filling also can be used in this kind of plate. The essential characteristics of each of these several modified constructions of fish-plates have substantially the same features—that is 100

to say, each fish-plate has a vertical inside and substantially outside wall which form a yielding fish-plate for preventing the bolts and nuts from working loose when the fish-plates are properly applied to the rail-joints.

Modifications may be made without departing from the spirit of my invention. The inside vertical walls of the fish-plates may be deflected from a vertical line, so as to allow the upper and lower edges of each fish-plate to properly engage the rails, and constructed so that the longitudinal central portion does not lie flat against the web of the rail. Other changes and modifications may be made without departing from the spirit of my invention.

What I claim as new, and desire to secure by Letters Patent, is—

1. In a fish-plate consisting of one piece of metal, provided at its upper edge with a return-bend the walls of which are out of contact with each other for engaging the under side of the tread of the rail, the lower edges of the fish-plate brought together at their lowest edges for engaging the flange of the rail, substantially as set forth.

2. A longitudinally rigid fish-plate composed of a single plate of metal, having at its upper edge a return-bend the walls of which are out of contact with each other, the lower edges of the return-bend being brought together, substantially as set forth.

3. A fish-plate composed of a single plate of metal, having at its upper edge a return-bend the walls of which are out of contact with each other, the space between the return-walls filled with relatively yielding material, the lower edges of the return-bend forming the walls of the plate brought substantially in contact with each other, the said plate having rigid edges when thus formed, substantially as set forth.

4. A fish-plate consisting of a single piece of metal, having an inverted-U-shaped bend in its width forming the walls substantially parallel with each other and brought substantially together at their lower edges, substantially as set forth.

5. A fish-plate consisting of a single piece of metal, having an inverted-U-shaped longitudinal bend forming the walls substantially parallel with each other, relatively yielding material inserted between the walls of the U-shaped fish-plate which are brought substantially into engagement with each other, combined, substantially as set forth.

6. In a railway-bed, fish-plates adapted for connection to adjacent ends of railway-rails, the said fish-plates being composed of two substantially parallel walls having at one edge of the space thereby inclosed a returned bend, the outer edges being brought together, the said plates being adapted to fit the lower angles of the tread and the upper angle of the base, substantially as set forth.

7. In a railway-joint, the adjacent ends of

railway-rails, in combination, with a pair of fish-plates each consisting of one piece of metal, provided at its upper side with a return-bend the walls of which are out of contact with each other for engaging the under side of the tread of the rail, the lower edges of the fish-plate brought together at their lowest edges for engaging the flange of the rail, substantially as set forth.

8. In a railway-joint, the adjacent ends of railway-rails, in combination, with a pair of fish-plates, each composed of a single plate of metal having at its upper edge a return-bend the walls of which are out of contact with each other, the lower edges of the return-bend brought together, the said fish-plate being rigid in its length, substantially as set forth.

9. The adjacent ends of the railway-rails, in combination, with a pair of fish-plates, each fish-plate composed of a single rigid-edged plate of metal having at its upper edge a return-bend the walls of which are out of contact with each other, the space between the return-walls filled with relatively yielding material, the lower edges of the return-bend forming the walls of the plate being brought substantially in contact with each other at their lower edges, substantially as set forth.

10. The adjacent ends of the railway-rails, in combination, with a pair of fish-plates, each fish-plate consisting of a single piece of metal having an inverted-U-shaped longitudinal bend forming the walls substantially parallel with each other and brought substantially together at their edges, substantially as set forth.

11. Adjacent ends of railway-rails, fish-plates adapted to connect the said rails, the same comprising a tubular member formed with walls substantially parallel and to engage the under edge of the tread and the upper edge of the base against the surface of the web and provided with apertures in the walls to receive means for securing them to the rail.

12. A fish-plate formed of metal with a return-bend in its center for engaging the under side of the head of the rail, walls being out of contact with each other and the space between the walls being filled with relatively yielding substance, substantially as shown.

13. A fish-plate formed of a tubular piece of metal, having an inverted-U-shaped bend in its upper vertical center for engaging the under side of the head of the rail, the inverted-U-shaped walls being formed out of contact with each other, the lower horizontal portion of the plate formed to engage the flange of the rail, the space between the inverted walls filled with a relatively yielding substance, substantially as set forth.

14. The adjacent ends of the railway-rails, in combination, with a pair of fish-plates, each fish-plate formed of a single piece of metal having an inverted-U-shaped bend in its upper vertical center for engaging the under side of

the head of the rail, the inverted-U-shaped walls being formed out of contact with each other, the lower horizontal portion of the plate formed to engage the flange of the rail, 5 the edges of the plate being brought into close engagement, substantially as set forth.

15. The adjacent ends of the railway-rails, in combination, with a pair of fish-plates, each fish-plate formed of a single piece of metal 10 having an inverted-U-shaped bend in its upper vertical center for engaging the under side of the head of the rail, the inverted-U-shaped walls being formed out of contact with each other, the lower horizontal portion of the plate 15 formed by close contact of the edges to engage the flange of the rail, the space between the walls filled with a relatively yielding substance, substantially as set forth.
16. A fish-plate adapted to connect adjacent 20 ends of rails comprised of a plate having a U-bend lengthwise, its edges being brought into engagement, and formed to lie adjacent to the

web of the rail and pierced for means to secure the same to the rails, the said fish-plate when thus formed being rigid lengthwise, but 25 having yielding outer walls between its edges.

17. A fish-plate consisting of a single piece of metal having a lengthwise-U-shape bend forming walls substantially parallel to each other and having its edges brought substan- 30 tially together.

18. A fish-plate comprising a tubular-like member formed to rest beneath the tread and above the base of the rail, having between such points walls substantially parallel but sepa- 35 rated, the said plate being longitudinally rigid but yielding laterally as to its outer wall.

In testimony whereof I affix my signature in presence of two witnesses.
